UNITED STATES PATENT OFFICE.

ALFRED E. HORMAN, OF NEW YORK, N. Y.

HAMMER.

Application filed February 16, 1922. Serial No. 537,129.

To all whom it may concern:

Be it known that I, ALFRED E. HORMAN, a citizen of the United States, residing at New York city, county of New York, State 5 of New York, have invented certain new and useful Improvements in Hammers, of which the following is a specification.

My invention relates to hammers. The principal object of the invention is to provide improved means for supporting and actuating the hammer head so as to permit a relatively long stroke of the head and to maintain the head in a vertical or upright position and thereby apply its force in the 15 most effective way.

Other objects, features and advantages will appear more fully in the following detailed description and appended claims.

Attention is hereby directed to the accompanying drawing forming a part of the specification and illustrating one embodiment of my invention.

Fig. 1 is a view partly in elevation and partly in vertical section of the said embodiment of the invention.

Fig. 2 is a section on line 2—2 of Fig. 1.

Fig. 3 is a section on line 3—3 of Fig. 2.

Referring to the drawing, the hammer head 1 is pivoted as shown at 2 and 3 respectively to an elongated supporting member or arm 4 and an extension 5 on an elongated supporting member or arm 6. The horizontal axes of the pivots 2 and 3 are, as shown, arranged in the same vertical 35 plane. The arm 4 is pivoted for up and down movement to a horizontal rod 7 along which the supporting member or arm 4 is movable horizontally to permit the hammer head to be positioned over different parts 40 of an anvil. The member 6 carries adjacent its rear end a shaft 8 carrying flanged rollers 9 bearing against the cams 10 which are movable along shaft 7 with the supporting member 4, the cams being also mounted 45 for movement along shaft 7 parallel to the shaft 7 and being held against rotation by said shafts. The cams 10 are so shaped as to cause the movement of the member 6 longitudinally with respect to the member 50 4 to the proper amount upon the up and down movement of the hammer head to maintain the pivots 2 and 3 in the same vertical plane and thereby maintain the hammer head vertical. The shaft 8 is fixed 55 against longitudinal movement with respect to the member 6 and a spring 11 presses

upon the said shaft to hold the rollers 9 in engagement with the cams 10. The spring 11, as shown, bears at one end upon a sleeve 12 surrounding the shaft 8 and at the other end upon an adjustable bearing 14 carried by the member 4. This bearing, as shown, is in the form of a screw threaded for longitudinal movement in the member 4 and adapted to be locked in adjusted position 65 by a nut 15 bearing upon a washer 16. The spring 11 tends to press the member 6 towards the left (referring to Fig. 1) and with the form of cam shown tends to lift the members 4 and 6 with the hammer head. 70 As the spring 11 tends to expand, it tends to move the rollers 9 towards the pivot shaft 7 and thereby to raise the hammer from the solid line position shown in Fig. 1. By adjustment of the tension of spring 11, 75 it is possible to regulate the force tending to move the hammer head upwardly. The member 4 as shown is provided with a longitudinal slot 17 in which the spring 11 and sleeve 12 are arranged. The member 80 6, as shown, is formed with a portion 6' surrounding the member 4 and with side portions 6² and 6³ projecting from the part 6' and bearing against the sides of the member 4. The supporting members 4 and 85 6 are desirably arranged co-axially with each other. They may be moved to reciprocate the hammer head in any suitable way in a vertical plane as by the cam 20 which, as shown, bears on arm 4 and is rotatable 90 about an eccentric axis as at 20'.

While I have shown a preferred embodiment of my invention it is to be understood that changes within the scope of the appended claims may be made therein without departing from the spirit of my invention. 95

Having thus described my invention, what I claim as new and desire to secure by Letters Patent is:

1. The combination of a hammer head, 100 elongated members connected thereto to support the same for up and down movement, and means comprising a cam coacting with one of said members to position the same to maintain the head vertical during its downward movement.

2. The combination of a hammer head, 110 elongated members connected thereto to support the same for up and down movement, means comprising a cam coacting with one of said members to position the same to maintain the head vertical during its down-

- ward movement, and means supporting said members for horizontal movement.
3. The combination of a hammer head, elongated movable members substantially coaxial with each other and connected to said head, and supporting means for said members controlling the movement thereof to maintain said head vertical during its downward movement.
10. 4. The combination of a hammer head, elongated movable members coaxial with each other and connected to said head, and supporting means for said members including a cam controlling the movement thereof to maintain said head vertical during its downward movement.
15. 5. The combination of a hammer head, elongated movable members substantially coaxial with each other and connected to said head, and supporting means for said members controlling the movement thereof to maintain said head vertical during its downward movement, said supporting means permitting horizontal movement of said members.
20. 6. The combination of a hammer head, elongated members connected thereto to support the same for up and down movement, means comprising a cam coacting with one of said members to position the same to maintain the head vertical during its downward movement, and means for causing movement of said members in a vertical plane.
25. 7. The combination of a hammer head, elongated movable members substantially coaxial with each other and connected to said head, supporting means for said members including a cam controlling the movement thereof to maintain said head vertical during its downward movement, and means for causing movement of said members in a vertical plane.
30. 8. The combination of a hammer head, elongated members connected thereto to support the same for up and down movement, and means comprising a cam coacting with one of said members and a spring to hold said member in operative relation to said cam to position said member to maintain the head vertical during its downward movement.
35. 9. The combination of a hammer head, elongated movable members substantially coaxial with each other and connected to said head, supporting means for said members including a cam controlling the movement thereof to maintain said head vertical during its downward movement, and means for causing movement of said members in a vertical plane.
40. 10. The combination of a hammer head, elongated movable members coaxial with each other and provided with means pivotally connecting the same to the head for movement relatively to the head about axes respectively in the same vertical plane, a pivotal support for one of said members and means comprising a cam controlling the movement of the other member to maintain said axes in the same vertical plane during the downward movement of the head.
45. 11. The combination of a hammer head, elongated movable members coaxial with each other and provided with means pivotally connecting the same to the head for movement relatively to the head about axes respectively in the same vertical plane, a pivotal support for one of said members, means comprising a cam controlling the movement of the other member to maintain said axes in the same vertical plane during the downward movement of the head, and means for causing movement of the head in a vertical plane.
50. 12. The combination of a hammer head, elongated movable members provided with means pivotally connecting the same to the head for movement relatively to the head about axes respectively in the same vertical plane, a pivotal support for one of said members, means comprising a cam controlling the movement of the other member to maintain said axes in the same vertical plane during the downward movement of the head, and means for causing up and down movement of the head.
- In testimony whereof, I have signed my name to this specification.

ALFRED E. HORMAN.
